UNITED STATES PATENT OFFICE.

HUBERT ZINS, OF WABASSO, MINNESOTA.

VETERINARY OBSTETRICAL FORCEPS.

Application filed November 3, 1927. Serial No. 230,815.

This invention relates to an obstetrical forceps adapted to be used for the purpose of delivering a pig, and has for one of its objects to provide a novel, simple and highly efficient instrument of this character which shall embody a pair of members pivotally and detachably connected together and provided with curved leg engaging beaks of arcuate formation and adapted when closed to overlap so as to prevent injury to the vagina during the insertion of the instrument, each member being adapted when separated to be used as a pig delivering instrument.

With the foregoing and other objects in view, the nature of which will appear as the description proceeds, the invention consists in the construction, combination and arrangement of parts hereinafter fully described and claimed, and illustrated in the accompanying drawing, wherein:

Figure 1 is a view in side elevation of the forceps,

Figure 2 is a top plan view of the forceps,

Figure 3 is a front end view of the forceps,

and

Figure 4 is a perspective view of the front end portion of one of the forceps members and its beak.

The forceps comprise elongated straight jaws 1 and 2 which have their rear end portions reversely bent and connected by a pivot 3. Handles 4 and 5 extend rearwardly from the jaws 1 and 2, respectively, and they are provided with hooked rear terminals 6 and 7, respectively, which are adapted to prevent the handles from slipping from the hands. The jaws 1 and 2 are provided at their front ends with oppositely extending and rearwardly curved beaks 8 and 9, respectively. Each of the beaks 8 and 9 has a flat inner lateral face 10 and a convex outer lateral face 11. The inner faces 10 are reversely inclined and contact when the jaws 1 and 2 are closed. The beaks 8 and 9 do not project laterally beyond the jaws 1 and 2, and when closed provide the forceps with a rounded front end. The jaws 1 and 2 are of circular formation in cross section, and are provided at their front ends with inner shoulders 12 directly in advance of which the free terminals of the beaks 8 and 9 are positioned when the jaws are closed.

In practice, the forceps are inserted into the vagina with the jaws 1 and 2 in closed relation. After the forceps are inserted into the vagina, the jaws 1 and 2 are opened and engaged with a leg or nose of the pig in a man-

ner to position the beaks 8 and 9 in rear of the leg or clamp on the nose. The jaws 1 and 2 are closed, and thereafter the delivery of the pig is effected by applying traction to the forceps. As the jaws 1 and 2 are circular in cross section, as the beaks 8 and 9 present the closed forceps with a rounded front end, as the beaks do not project laterally beyond the jaws, and as the beaks are arranged in overlapped relation when the jaws are closed, the forceps may be readily inserted into the vagina without danger of injury thereof.

The pivot 3 is so constructed that it may be readily removed when it is advisable or necessary to use but one member of the forceps. Each member of the forceps consists of a shank, a handle, and a curved beak. The forceps are also adapted, as will be apparent, to be used for the purpose of delivering the fetus of dogs, cats and other small animals.

It should be understood that the drawing is merely illustrative and does not pretend to give exact proportions. Furthermore, the said drawing is illustrative of a preferred construction, it being my expectation that various changes and modifications may be made without departing from the spirit and scope of my invention.

What is claimed is:

1. A forceps comprising a pair of pivotally connected jaws provided at their front ends with beaks, the beak of one jaw extending therefrom in the direction of the other jaw, and the beaks being adapted to occupy an overlapping relation when the jaws are closed.

2. A forceps comprising a pair of pivotally connected jaws provided at their front ends with beaks, the beak of one jaw extending therefrom in the direction of the other jaw, and the beaks being rearwardly curved and adapted to occupy an overlapping relation when the jaws are closed.

3. A forceps comprising a pair of pivotally connected jaws provided at their front ends with shoulders and beaks, the beak of one jaw extending therefrom in the direction of the other jaw, and the beaks being adapted to occupy an overlapping relation with their free terminals in advance of the shoulders when the jaws are closed.

4. A forceps comprising a pair of pivotally connected jaws provided at their front ends with shoulders and beaks, the beak of one jaw extending therefrom in the direction of the other jaw, and the beaks curving rear-

wardly and adapted to occupy an overlapping relation with their free terminals in advance of the shoulders when the jaws are closed.

5. A forceps comprising a pair of pivotally connected members provided with reversely and rearwardly curved blunt beaks having flat inner lateral surfaces and convex outer lateral surfaces, the inner surfaces of the beaks being reversely inclined and contacting 10 when the beaks are in closed relation.

6. A forceps comprising elongated jaws of circular formation in cross section and pivotally connected, handles carried by the rear

ends of the jaws, and reversely and rearwardly curved beaks carried by the front ends 15 of the jaws, the beaks being adapted to overlap when in closed relation and provided with reversely inclined flat inner faces and with convex outer lateral faces, the beaks being arranged wholly within the planes of the lateral sides of the jaws, and the jaws being provided with shoulders opposite the free ends of the beaks. 20

In testimony whereof I affix my signature.

HUBERT ZINS.
